tories, Incorporated, Boonton, N. J., a corpora-
tion of New Jersey

Application May 28, 1932. Serial No. 614,249

17 Claims. (Cl. 178—44)

This invention relates to radio receivers and particularly to a receiver having improved characteristics from the standpoint of selectivity.

The commercial radio receivers are characterized by a marked variation of selectivity with frequency and, in some instances receivers which fail to provide satisfactory selectivity at the high frequency end of the present broadcast band of from 550 to 1500 kilocycles tune so sharply at the lower frequencies as to introduce audio distortion by cutting of the side bands. Good audio quality, particularly when separate reproducers are employed for the lower and higher audio frequencies, necessitates an approximately uniform transmission of a band of frequencies but band pass transmission or low selectivity is not possible over the entire tuning range. The general practice has therefore been to effect some compromise between the conflicting design requirements and, as a result, the selectivity of the known receivers varies with frequency and may be either too low to prevent interference between adjacent channels or too high for good tone quality.

An object of the present invention is to provide a radio receiver in which the selectivity is under manual control and, for any setting of the manual control, is substantially constant over the tuning range. An object is to provide a variable band width transmission system including a plurality of cascaded tuned circuits, and in which certain of the tuned circuits exhibit a substantially constant selectivity over the signal frequency range and other circuits include elements for varying the width of the transmitted band of frequencies, the transmission efficiency of the latter circuits being independent of the frequency of the received signal. A further object is to provide a superheterodyne receiver including a carrier frequency amplifier which exhibits a constant selectivity over the entire signal frequency band, and an intermediate frequency amplifier having cascaded tuned circuits which may be manually adjusted to vary the width of the band of frequencies for which the transmission efficiency is substantially constant. More specifically, an object is to provide a superheterodyne of the type stated in which the tuned carrier frequency circuits include circuit elements for automatically introducing losses when tuned to lower frequencies, thus preventing variation of selectivity with frequency. A further specific object is to provide a coupled circuit capable of adjustment to vary the width of the resonance curve without substantial change in the shape of the resonance curve and

without change in the natural resonant frequency of the coupled circuits. More specifically, an object is to provide coupled circuits of the type last stated in which the coefficient of coupling between the circuits is so varied as to change the width of the resonance band without changing the natural resonant frequency, and the power factors of the circuits are simultaneously varied to prevent a change in the general shape of the resonance curve.

These and other objects and advantages of the invention will be apparent from the following specification, when taken with the accompanying drawing, in which,

Fig. 1 is a circuit diagram of one embodiment of the invention,

Fig. 2 is a curve sheet showing selectivity curves for different power ratios of the coupled circuits, and

Fig. 3 is an equivalent diagram of one pair of coupled circuits.

In the drawing, the reference character 1 identifies a carrier wave or radio frequency amplifier tube which precedes the first detector 2 of a superheterodyne receiver; the beat frequency signals produced in tube 2 by beating the carrier wave with local oscillations from the oscillator 3 being passed to the cascaded tubes 4, 5 of an intermediate frequency amplifier, and then to the second detector 6.

The input system between the collector system AG is of the type which reduces the frequency variation of the input system gain, and preferably this result is obtained by including, in series, between the collector A and the tuned input circuit of tube 1, a choke 7 which resonates with the antenna capacity at a frequency slightly above the highest frequency to which the receiver may be tuned.

The tuned input circuit of tube 1 comprises an inductance 8 connected between the control grid and cathode, and shunted by a tuning condenser 9 in series with a parallel circuit comprising a resistance 10 and shunt capacity 11. The coupling between the amplifier tube 1 and detector 2 preferably is of the twin-circuit type, i. e., includes two circuits substantially identical with the input circuit of tube 1 and coupled with somewhat less than critical shape coupling. Inductance 8' of the first twin circuit is coupled to 105 the plate coil 12 of tube 1.

The high potential terminals of the twin inductances 8' are coupled by a capacity 13 and, between the low potential terminals of each twin inductance 8 and a common coupling capacity 14, 110

automatic losser circuits comprising a resistance 10 and condenser 11 are provided. The tuning condensers 9 of the twin circuits are connected between ground and the respective high potential terminals of the twin inductances. This twin circuit, except for the addition of the losser elements, is substantially identical with the circuit described in the copending application of Paul O. Farnham, Serial No. 461,020, filed June 13, 1930. 10 As described in said application, the two coupling capacities 13, 14 may be so related as to provide an approximately constant coupling between the circuits for all frequencies. The purpose of the twin circuits is, of course, to provide increased selectivity. The several tuning condensers 9 of the carrier wave circuits and the similar tuning condenser 9' of the oscillator 3 are preferably mechanically connected, as indicated by broken lines 15, as is customary in single dial tuning systems.

Before proceeding to the description of the intermediate frequency amplifier, it is to be noted that the several losser circuits 10, 11 in the carrier wave circuits automatically increase the effective resistance of the circuits as they are tuned to lower frequencies, thus maintaining a substantially constant selectivity over the entire carrier frequency band. The input circuit choke 7 reduces the frequency variation of the gain in the carrier wave amplifier. The transmission from the collector structure to the input terminals of the intermediate frequency amplifier is therefore substantially constant over the entire carrier frequency band.

35 This condition makes it possible to obtain a uniform control, over the entire carrier frequency band, of the overall selectivity of the receiver by an appropriate design of an intermediate frequency amplifier for passing a band of frequencies 40 of controlled width.

The intermediate frequency couplings between tubes 2 to 6 are preferably of the transformer type. The primary windings 16 and secondary windings 17 of the several transformers are preferably identical, and each winding is tuned to the same resonant frequency by trimming condensers 18. One of the intermediate frequency transformers, as shown the transformer between the amplifier 5 and second detector 6, may be of the usual fixed type, and only the other two transformers are designed for manual adjustment to vary the width of the resonance band.

50 As indicated by the arrows 19, the magnetic coupling of the windings of the transformers associated with the tube 4 may be adjusted to vary the selectivity of the receiver. To prevent substantial change in the shape of the resonance band as its width is varied, the tuned circuits of these transformers include adjustable series resistances 20, and the adjustable control elements of the variable resistances and variable couplings are all mechanically connected as indicated by broken lines 21, for simultaneous operation. Since the changes in the coupling between the windings of a transformer will not alter the resonant frequency of the individual windings, the natural resonant frequency of the transformer is not affected by changes in the coupling. Increasing the coupling beyond critical shape 65 would, however, result in the production of two peaks separated by a depression which increases in magnitude with an increase in the coupling coefficient, i. e., the shape of the resonance curve would change with its width.

70 75 The variable resistances 20 prevent or reduce

this variation in the shape of the resonance curve, and their method of operation will be apparent from a consideration of Figs. 2 and 3.

The variable transformers provide alternating current circuits, as shown in Fig. 3, which include inductance, capacity and resistance, the alternating voltage E_0 impressed on the first circuit developing a voltage E across the condenser of the second circuit. The impedances of the coupled circuits are designated as L_1, C_1, R_1 , and as L_2, C_2, R_2 , respectively. As is well known, the relationships between the values of the several characteristics of the Fig. 3 circuit may be expressed by the following equations:

Coefficient of coupling;

$$\tau = \frac{M}{\sqrt{L_1 L_2}}$$

Power ratio of circuits;

$$\eta_1 = \eta_2 = \eta = \frac{R}{\omega L}$$

when $R_1 = R_2$ and $L_1 = L_2 = L$
Resonant frequency;

$$\omega_0 = \frac{1}{\sqrt{L_1 C_1}} = \frac{1}{\sqrt{L_2 C_2}}$$

Transmission efficiency at ω_0 :

$$T_0 = \frac{E}{E_0} \text{ at } \omega_0$$

Transmission efficiency at ω :

$$T = \frac{E}{E_0} \text{ at } \omega,$$

where ω may be any frequency off resonance.

Data for selectivity curves is obtained by measuring the transmission efficiency for a particular resonance frequency and for frequencies off resonance, the curve being usually plotted between the transmission efficiency and the frequencies off resonance. An examination of such curves will show that the selectivity increases as the width of the plotted curve decreases and, for purposes of analysis, it is usual to determine the width of the frequency band, $\Delta\omega$, for which a given ratio of transmission

$$\frac{T_0}{T}$$

125 obtains. For example, if the resonant frequency is 1000 kilocycles, the selectivity of the circuit may be expressed in terms of the width of band between those frequencies, above and below 1000 kilocycles, for which the transmission efficiency is only one-half of that for 1000 kilocycles. Experience has shown that the width $\Delta\omega$ of the band of equal transmission varies with the resonant frequency.

130 It is possible, however, to plot selectivity curves which are equally applicable to all frequencies by a suitable choice of the ordinates against which the transmission efficiency is plotted. This system was followed in preparing the selectivity curves of Fig. 2. Designating the ratio of equal transmission band width to resonant frequency as

$$\beta = \frac{\Delta\omega}{\omega_0},$$

135 and dividing this ratio by the power factor η of the coupled circuits, units

$$\frac{\beta}{\eta}$$

140 are obtained which may be utilized as ordinates

for generalized selectivity curves for coupled circuits such as shown in Fig. 3. The three curves shown in Fig. 2 are selectivity curves for different adjustments of the variable factors of one 5 of the coupling circuits of the intermediate frequency amplifier.

Curve A of Fig. 2 shows the selectivity of one pair of coupled circuits when the coupling M , and the ratio

10

$$k = \frac{\tau}{\eta}$$

was substantially zero. Curve B was plotted from data obtained when the circuit was adjusted to 15 make the factor k equal to unity, and curve C was plotted for an adjustment corresponding to k equal to two. The important fact demonstrated by these curves is that the shape of the resonance curves, or the selectivity curves, is dependent 20 upon the resistance or power factors of the coupled circuits. For example, if the values of the coupling M and the resistances 20 are such that curve B represents the selectivity of the system, and the coupling M is then doubled without 25 increasing the resistances 20, the selectivity of the system will be represented by curve C, since the ordinates

$$\frac{\beta}{\eta}$$

30

are not altered by the increase in the coupling M . This operation does not obtain, however, with the circuits shown in Fig. 1 when the effective values of the resistances 20 are increased 35 simultaneously with an increase in the coupling M . By increasing the circuit resistances R_1 , R_2 in the same ratio as the increase in the coupling M , the selectivity is still represented by the curve B but the width of this curve is increased since 40 the ordinates

$$\frac{\beta}{\eta}$$

are proportionately decreased by the increase in 45 the power factor

$$\eta = \frac{R}{\omega L}$$

The width of the resonance curve is thereby 50 increased but its shape remains unchanged.

When the power factors of the circuits and their coupling are varied simultaneously and at the same rate, all of the intermediate frequency couplings may be adjusted to control the band width without altering the shape of the resonance curve. Alternatively, the curves of Fig. 2 show that the shape of the selectivity curve for a plurality of cascaded circuits will not be substantially changed if the couplings between a part only of the cascaded circuits are changed without changing the resistances of the circuits. For example, a change of one circuit from operation on curve B to operation on curve C will produce a depression between two peaks, but this depression will be compensated if another circuit is continuously operated to provide the selectivity represented by single peak curve B.

The invention therefore provides a transmission system or radio receiver that may be tuned over a band of frequencies, and which has the novel characteristic of a controlled selectivity which, for any given adjustment, is constant over the frequency band. The selectivity may be increased or decreased at will according to the particular conditions existing at the time signals are

being received. When the signals are of such magnitude as to exclude interference from adjacent channels and to swamp out static, the receiver may be adjusted for low selectivity, i. e., to pass a relatively wide band of frequencies with approximately uniform transmission, thus ensuring good tone quality. If the receiver is tuned to another and comparatively weak signal, or if the existing conditions outside the receiver so change as to result in interference or noise in the reproduction of the same signal, the selectivity may be increased to eliminate the disturbing factors by an appropriate adjustment of the couplings and resistances of the variable bandwidth transmission circuits. This adjustment does not affect the tuning of the receiver as the variable transmission circuits have the same natural resonance frequency for all adjustments.

The invention is applicable to other types of transmission circuits, either tuned to a single frequency or tunable over a band, and the selectivity adjustment may be continuously variable or variable by set increments. The invention is not restricted to the particular circuit arrangement herein shown and described, as many changes in the circuit elements, their relative arrangements and magnitudes fall within the spirit of our invention as set forth in the following claims.

We claim:

1. In a transmission system, the combination with a pair of tuned circuits, and a reactive coupling between said circuits, of means for simultaneously controlling both the shape and the width of the selectivity curve of said circuits without altering the natural resonant frequency thereof.

2. In a transmission system, the combination with a pair of tuned circuits, and reactive coupling between said circuits, of means for simultaneously changing the magnitude of the coupling between said circuits and the resistances of said circuits, thereby to control both the width and the shape of the selectivity curve of said circuits.

3. In a transmission system the combination with two tuned circuits each including adjustable resistance, and magnetic coupling between said circuits, of means for simultaneously adjusting the coupling between said circuits and the effective magnitudes of the said resistances.

4. The invention as set forth in claim 3, wherein said means adjusts the coupling and the resistances at such relative rates that the shape of the selectivity curve of said circuits remains constant as its width is altered by variation of said coupling.

5. In a tunable system for the transmission of signals falling within a band of frequencies, the combination with a tuned amplifier having a substantially constant selectivity for the entire frequency band, of means adjustable at will to determine the band width of over-all transmission of the system, said means comprising a second tuned amplifier, and means manually adjustable at will during operation of the receiver to determine the selectivity of the said second amplifier.

6. The invention as set forth in claim 5, wherein said first amplifier is a radio frequency amplifier tunable over a band of frequencies, and said second amplifier is an intermediate frequency amplifier tuned to a fixed frequency.

7. In a tunable system for the transmission of modulated signals falling within a band of carrier frequencies, the combination with a car-

- rier wave amplifier including a plurality of tunable circuits having a substantially constant selectivity over the entire carrier frequency band, of a second amplifier including a plurality of circuits tuned to resonate at a fixed frequency, means for adjusting the band width of transmission of said second amplifier, and means adjustable simultaneously with said first means to maintain said second plurality of circuits in resonance at said fixed frequency for all adjustments of said first means. 80
3. A carrier wave receiver of the type tunable over a band of frequencies and including a plurality of cascaded tubes coupled by tuned circuits, and adjustable impedances in certain of said circuits for determining the overall selectivity of said receiver, characterized by the fact that a plurality of said adjustable impedances are simultaneously adjustable to maintain the overall selectivity constant throughout the tuning range of said receiver. 85
9. In a carrier wave receiver tunable over a band of frequencies, the combination with a plurality of amplifier tubes coupled in cascade by resonant circuits, of means adjustable to determine the overall selectivity of the receiver, and means substantially preventing variation of selectivity with frequency throughout the range of selectivity adjustment afforded by said adjustable means. 90
10. In a carrier wave receiver, a plurality of cascaded amplifiers and couplings between adjacent amplifiers, the coupling between one pair of adjacent stages comprising a pair of circuits tuned to the frequency of a desired signal, reactance coupling said circuits to each other, and means for adjusting the width of the selectivity curve of said coupled circuits without change in the shape of said curve. 95
11. In a carrier wave receiver, a plurality of cascaded stages and couplings between adjacent stages, the coupling between one pair of adjacent amplifiers comprising a pair of circuits tuned to the frequency of a desired signal, reactance coupling said circuits to each other, adjustable resistances in each of said circuits, and means for adjusting the effective magnitudes of the said resistances and of said coupling reactance. 100
12. In a tuned carrier wave receiver, a plurality of cascaded coupling circuits having an overall transmission efficiency corresponding to not more than critical shape coupling, certain of said coupling circuits including a pair of reactively coupled circuits, means for adjusting the magni- 105
- tude of the reactive coupling between said pair of circuits, and means operable throughout the range of adjustment of the magnitude of the said reactive coupling for maintaining the overall transmission efficiency within values corresponding to not more than critical shape coupling. 110
13. In a tuned carrier wave receiver, the combination of a pair of vacuum tubes, an output circuit for one tube, a tuned input circuit for the second tube, reactance coupling said circuits in a degree corresponding to approximately but not in excess of critical shape coupling, adjustable means for increasing the magnitude of said coupling reactance, and means adjustable simultaneously therewith for maintaining the coupling between said circuits at less than critical shape coupling. 115
14. In a carrier wave receiver tunable over a band of frequencies, a plurality of stages tuned to the same frequency and each having a selectivity not in excess of critical shape coupling, means including an adjustable impedance for decreasing the selectivity of one of said stages, and adjustable means for preventing said decrease in selectivity from decreasing the overall selectivity of said cascaded stages to less than that corresponding to critical shape coupling, said means being simultaneously adjustable at the will of the operator of the receiver. 120
15. The invention as set forth in claim 14, wherein said last means prevents the selectivity of the stage of decreased selectivity from decreasing to less than that corresponding to critical shape coupling. 125
16. In a transmission system, the combination with a tuned carrier wave amplifier having an approximately constant selectivity over the entire frequency band, of means for adjusting the overall selectivity of said system to different values which remain constant over the entire frequency band to which said carrier wave amplifier may be tuned, said means including a second amplifier, and means for adjusting the selectivity of said second amplifier and the shape of the selectivity curve thereof. 130
17. The invention as set forth in claim 16, wherein said second amplifier includes a pair of circuits coupled by a reactance and each circuit includes an adjustable resistance, and said last means comprises means for simultaneously varying the magnitude of said reactance and said resistances. 135
